UNITED STATES PATENT OFFICE.

RICHARD J. FLINN, OF WEST ROXBURY, MASSACHUSETTS.

GAGE-COCK FOR STEAM-BOILERS.

SPECIFICATION forming part of Letters Patent No. 680,993, dated August 20, 1901.

Application filed May 28, 1900. Serial No. 18,220. (No model.)

To all whom it may concern:

Be it known that I, RICHARD J. FLINN, of West Roxbury, in the county of Suffolk and State of Massachusetts, have invented certain new and useful Improvements in Gage-Cocks for Steam-Boilers, &c., of which the following is a specification.

This invention has for its object to provide an adjustable outlet whereby either the liquid or the gaseous contents of a steam-boiler or other receptacle intended to contain a liquid, such as water, and gaseous fluid, such as steam, may be allowed to escape wholly or in part from the receptacle.

15 The invention is intended, primarily, for a water-level indicator for a steam-boiler; but it may be used for other purposes, as hereinafter specified.

The invention consists in the combination, 20 with a boiler or other receptacle, of a movable outlet fitted to communicate with the interior of the receptacle and adjustable so that its inner or receiving end may be immersed in the liquid in the receptacle or raised above the liquid to communicate with the space above it, the outlet permitting the escape of the liquid when in one position and the gas when in another position.

Of the accompanying drawings, forming a 25 part of this specification, Figure 1 represents a sectional elevation of an apparatus embodying my invention. Figs. 2 and 3 represent similar views showing different embodiments of my invention.

30 Referring first to Fig. 1, *a* represents a receptacle, such as a steam-boiler, and *b* represents an external receptacle connected at the upper and lower portions with the receptacle *a* by the connections *c* *d*, the arrangement 35 being such that liquid will stand at the same level in each receptacle. In the top of the receptacle *b* is a stuffing-box *e*, in which a tube *f* is vertically movable. The lower end of said tube is open, and its upper end communicates with a casing *g*, having an outlet *h* and a valve-seat *i*.

40 *j* represents a valve, which is adjustable in the casing *g* by means of a screw-threaded connection between its stem *j'* and the upper 45 portion of the casing. The tube *f* and casing *g*, with its valve *j*, may be raised or lowered in the stuffing-box *e*, so that the lower end of

the tube *f* may be immersed in the liquid in the receptacle *b* or may be raised above the liquid. In the former case the opening in 55 the valve *j* will permit a discharge of liquid through the outlet *h*, while in the latter case the opening of the valve will permit the discharge of steam through said outlet.

k represents a graduated vertical guide 60 fixed to the receptacle *b*, and *l* represents a sleeve affixed to the casing *c* and embracing the guide *k*.

The above-described device may be used as a water-level indicator or gage-cock for a 65 boiler. When it is desired to ascertain the height of the water-level in the receptacles *a* and *b*, the operator opens the valve *j*. If the lower end of the tube *f* is above the water-level, steam will escape through the outlet *h*. 70 The operator by depressing the tube *f* until the flow of steam ceases and the flow of water commences will be able by consulting the graduated guide *k* to ascertain the exact height of the water-level, said guide being 75 marked to indicate, in co-operation with the sleeve *l*, the exact height of the lower end of the tube *f* above the bottom of the receptacle *b*.

In Fig. 2 is shown a different construction, 80 in which a tube *m* is journaled to rotate in the stuffing-box *n* in one side of a boiler or other receptacle *a*, the said tube having a vertical extension *m'* within the boiler, the lower end of this extension opening into either the steam or water space of the boiler, according to the adjustment of the device. The casing *n* is affixed to the outer end of the tube *m* and has an outlet *o*, a valve-seat *p*, and a valve *q*, the latter having a threaded stem *q'* engaging the internally-threaded upper portion 90 of the casing *n*. In this case the operator turns the tube *m* to vary the height of the receiving end of the extension *m'* by swinging the latter in a vertical plane, the result being the same as that described in connection with the construction shown in Fig. 1. The casing *n* is provided with an indicator-arm *s*, which co-operates with a graduated segmental scale-plate *t'*, affixed to the boiler *a*. 95

In Fig. 3 I show the boiler provided with 100 two stand-pipe sections *u* and *u'*, having stuffing-boxes *v* *v'* and a tube *w* fitted to slide in said stuffing-boxes and provided with a cock-easing *x*, having an outlet *x'*, a valve-

- seat, and a valve x^2 . The liquid stands at the same level in the tube w as in the boiler a , and the operator by moving the tube up or down and opening the valve x^2 causes either steam or water to emerge from the outlet x' , according to the height of the water-line. A pointer y on the tube w co-operates with the vertical guide z , affixed to the boiler a .
- 10 The above-described apparatus may be used in connection with other receptacles besides steam-boilers. For example, it may be used in connection with holders for carbonated or aerated beverages under pressure to enable either liquid or gas to be withdrawn from the receptacle, the liquid being withdrawn when the adjustable tube is below the liquid-level and gas when the tube is above said level.
- 20 In each of the figures of the drawings the construction is such that the valve may be operated and the position of the inlet varied independently or together by one hand of the operator. With the construction shown in Fig. 1 the operator may slide the tube f up or down by means of the handle on the valve-stem without turning the valve to open it, or the valve may be opened or closed while the tube is being slid up or down. With the form shown in Fig. 2 the operator may grasp the handle of the valve-stem and either while opening or closing the valve or holding it seated may press laterally on the handle of the valve-stem, so as to swing the casing n and turn the tube m and its extension m' . When the form shown in Fig. 3 is employed, the vertical adjustment of the tube w may

be effected by pressing up or down upon the handle on the valve-stem either while the valve remains closed or while simultaneously turning the handle to open or close the valve.

I claim—

1. An apparatus of the character specified, comprising a reservoir and a movable conduit having an inlet communicating with the interior of the reservoir, and an outlet outside of the reservoir, said inlet being adjustable toward and from the bottom of the reservoir and adapted to receive the liquid or gaseous contents of the reservoir, a valve for controlling the said outlet and means whereby the valve may be operated and the position of the inlet varied, independently or together, by one hand.

2. An apparatus of the character described, comprising a reservoir and a movable conduit having an inlet communicating with the interior of the reservoir, an outlet outside the reservoir, said inlet being adjustable toward and from the bottom of the reservoir and adapted to receive either the liquid or the gaseous contents of the reservoir, an indicator whereby the observer may determine the height of the liquid-level, a valve for controlling the said outlet and means whereby the valve may be operated and the position of the inlet varied, independently or together, by one hand.

In testimony whereof I have affixed my signature in presence of two witnesses.

RICHARD J. FLINN.
